Application January 24, 1947, Serial No. 724,210

7 Claims. (Cl. 35—26)

1

This invention relates to a perspective aid device.

The chief object of this invention is to provide guide lines for the draftsman or artist to aid and assist in the creation of a true angular perspective image or representation.

The chief feature of the present invention resides in the provision of an adjustable length horizon line, in lineal perspective drawing, having two vanishing points in that line, the distance between said points determining the length of that line and the resulting perspective utilized for the drawing to be made.

Another feature of the invention resides in its extreme simplicity in production and use as set forth herein.

Other objects and features of the invention will be more fully mentioned and described in the description to follow.

The full nature of the invention will be understood from the accompanying drawings and the following description and claims.

In the drawings—

Fig. 1 is a perspective view of a base structure with one set of guide lines thereon, herein shown as applied to a movable transparent or translucent element.

Fig. 2 is a similar view of a translucent or transparent element for use with the parts shown in Fig. 1.

Fig. 3 is a plan view of the complete device to which has been applied tracing paper or cloth upon which has been formed a partial perspective image.

Fig. 4 is an enlarged section showing one embodiment of the base.

In Figs. 1, 3 and 4, 10 indicates a base or board element of any suitable material and provided on two opposite sides with perspective element retainers or rails 11. Herein same is shown as a channel with a wider flange 12, a web 13 and a narrow flange 14.

The spacing between flanges is just sufficient to accommodate base 10 and one or two of the guide elements as hereinafter described. The base board is suitably apertured at 15, see Fig. 4, and the flange 12 is similarly apertured and tapped as at 17 to take screws 16. Other forms of channel-base connection may be utilized, that disclosed herein being representative only because the channels shown are duplicates.

Also the embodiment selected for illustration contemplates two drafting guide elements. Herein 18 indicates the so-called lower element. It is provided with a vanishing point VP1 at one

5 side and a horizontal horizon line HL1 intermediate the side edges. This element 18 includes transverse spaced lines 19 and angle lines 20 spaced from each other and the horizon line and at opposite sides thereof as shown.

The foregoing lines and vanishing point may be permanently applied to base 10 whenever desired. However, it is preferred to utilize a separate element and have same slidably to and from upon the base for adjusting the position of point VP1 thereon.

A translucent or transparent sheet 21, see Figs. 2 and 3, includes at the opposite end vanishing points VP2 included in intermediate horizon line 15 HL2. This element includes transverse spaced lines 23 and angularly disposed lines 24. From inspection it will be noted that if the horizon lines are medianly disposed on each element one element is a duplicate of the other although in use, see Fig. 3, same are oppositely disposed. Element 21 also is slidable over element 18 and is guided and retained by channels 11.

As illustrated in Fig. 3 the guide lines are adjusted by moving one or both elements until the distance between vanishing points is that desired or required and of course that determines the length of the horizon line for then lines HL1 and HL2 coincide or register.

A sheet of tracing material 25 is suitably secured to the exposed face of member as by "Scotch" tape 26 or the like. Then the image is formed by pencil 27 or like instrument as illustrated in Fig. 3.

All vertical lines of such image are parallel 35 to transverse lines 19 and 23 exposed through sheet 25. The several angle lines 20 and 24 are similarly exposed and the image lines corresponding to the angular perspective are approximately parallel thereto or the horizon line, all as shown.

40 While the invention has been illustrated and described in great detail in the drawings and foregoing description, the same is to be considered as illustrative and not restrictive in character.

45 The several modifications described herein as well as others which will readily suggest themselves to persons skilled in this art, all are considered to be within the broad scope of the invention, reference being had to the appended claims.

The invention claimed is:

1. An adjustable perspective drawing device including in combination two superposed elements, each having parallel spaced lines, a horizon line positioned intermediately on one of the

elements and transverse to all first mentioned lines therein, and other lines on the said one element and inclined to the horizon line, the said inclined lines being disposed at opposite sides of the said horizon line and projectively intersecting same at a vanishing point therein, the horizon lines of both elements registering, the vanishing points being disposed oppositely relative to each for common horizon line length determination, the uppermost of said elements at least being translucent for lower element line exposure therethrough, the elements being slideable relative to each other for horizon line length variation.

2. A device as defined by claim 1 wherein both elements are substantially identical, the horizon lines halving the spaced lines.

3. A device as defined by claim 1 wherein the inclined lines depart from the horizon line by progressively increasing angles, the angular increase being substantially equal.

4. A device as defined by claim 1 wherein the inclined lines depart from the horizon line by progressively increasing angles, the angular increase being substantially equal, and both elements are substantially identical, the horizon lines halving the spaced lines.

lines leaving the spaced lines.

5. A device as defined by claim 1 wherein the lowermost element comprises a base with upper and edge disposed trackways to slidably support the uppermost element. 30

6. A device as defined by claim 1 wherein the lowermost element comprises a base with upper and edge disposed trackways to slidably support the uppermost element, the lowermost element including a duplicate of the uppermost element in reversed relation and slidable in the trackways, the horizon lines bisecting the parallel lines.

7. A device as defined by claim 1 wherein the lowermost element comprises a base with upper and edge disposed trackways to slidably support the uppermost element, the lowermost element including a duplicate of the uppermost element and disposed in reversed relation thereto and slidable in the trackways, the horizon lines bisecting the parallel lines, the inclined lines departing from the horizon lines by progressively increasing angles, the angular increase being substantially equal.
